UNITED STATES PATENT OFFICE.

DE WITT C. FRANKLIN, OF MAYSVILLE, KENTUCKY.

DENTAL MOUTH-MIRROR ATTACHMENT.

SPECIFICATION forming part of Letters Patent No. 726,895, dated May 5, 1903.

Application filed June 27, 1902. Serial No. 113,450. (No model.)

To all whom it may concern:

Be it known that I, DE WITT C. FRANKLIN, a citizen of the United States, residing at Maysville, in the county of Mason and State of Kentucky, have invented a new and useful Mouth-Mirror Attachment, of which the following is a specification.

The object of the present invention is to provide an improved attachment for dental mouth-mirrors for the purpose of holding or retaining filling material in the cavity of a tooth while it is being packed or condensed.

A further object of the invention is to provide an attachment of such nature that it may be readily adjusted to any desired position on a peripheral line of the mirror without removal and without the necessity of adjusting any auxiliary securing devices.

With these and other objects in view the invention consists in the novel construction and arrangement of parts hereinafter described, illustrated in the accompanying drawings, and particularly pointed out in the appended claims.

In the accompanying drawings, Figure 1 is a perspective view of a dental mouth-mirror provided with an adjustable holding-finger in accordance with my invention. Fig. 2 is a similar view looking from the rear of the mirror-frame and illustrating the manner of securing the adjustable holding-finger in position. Fig. 3 is a detail perspective view of the holding-finger detached. Fig. 4 is a face view of the mirror, illustrating in dotted lines a number of positions to which the holding-finger may be adjusted without removing the same from the mirror.

Similar numerals of reference are employed to indicate corresponding parts throughout the several figures of the drawings.

In the drawings, 1 designates an ordinary form of dental mouth-mirror having the usual metallic casing and provided with an elongated handle 2. At the exact center of the rear face of the casing is secured a pin or stud 3, bent at its upper end to form an elongated head 4, and on said pin is mounted the holding attachment forming the subject of the present invention. The attachment is in the form of a small plate 5, having near one end a slot 6, which may be fitted over the

head 4 and then turned to any angular position with the pivot-pin as a center without danger of accidental removal, it being impossible to remove the plate until the elongated slot is moved directly into alignment with the head of the pin 4. The plate is provided with three arms 7, 8, and 9, all of which embrace the edge of the mirror-casing, the central arm being bent up at an approximately right angle to the face of the mirror to form a finger 8 and this finger being bent at its upper end in any suitable manner in order that it may be employed as a holder to retain the filling material in position at the beginning of the plugging operation.

The attachment is formed of spring metal, and the arms 7, 8, and 9 are so arranged as to snugly embrace the peripheral wall of the mirror-casing to retain the device in position by friction, and while the single arm 8 may be employed for the purpose the addition of the two side arms serves to steady and more firmly hold the attachment in place.

The attachment may be moved to any angular position on the mirror-casing and will be retained in its adjusted position by frictional contact with the casing, and in use it is merely necessary to turn the attachment to the desired point without removal from the mirror and without the necessity of adjusting any auxiliary clamping or holding devices.

While the construction herein described, and illustrated in the accompanying drawings is the preferred form of the device, it is obvious that various changes in the form, proportions, size, and minor details of construction may be made without departing from the spirit or sacrificing any of the advantages of the invention.

Having thus described my invention, what I claim is—

1. The combination with a dental mirror, of the casing having a central pivot-pin, a plate pivotally mounted thereon and having a plurality of arms embracing the edge of the mirror-casing, one of said arms carrying a holding-finger, substantially as specified.
2. The combination with a dental mirror, of the casing, a centrally-disposed pivot-pin having an elongated head, a slotted plate mounted on said pin and adjustable circum-

ferentially of the mirror, a plurality of spring-arms forming a part of the plate and embracing the edge of the mirror-casing, one of said arms carrying a holding-finger, substantially as specified.

3. A dental mirror attachment comprising a plate of spring-metal having at one end an elongated slot and provided at the opposite end with a plurality of curved arms one of

the body of the plate to form a holding-finger.

In testimony that I claim the foregoing as my own I have hereto affixed my signature in the presence of two witnesses.

DE WITT G. FRANKLIN.
